(57) **CLAIM**

The ornamental design of an liquid cooled motor, as shown and described.

DESCRIPTION

FIG. 1 is a perspective view of an liquid cooled motor showing our new design; and

FIG. 2 is a right side view of the liquid cooled motor of FIG. 1;

FIG. 3 is a left side view of the liquid cooled motor of FIG. 1;

FIG. 4 is a bottom view of the liquid cooled motor of FIG. 1;

FIG. 5 is a top view of the liquid cooled motor of FIG. 1.

FIG. 6 is a front view of the liquid cooled motor of FIG. 1; and,

FIG. 7 is a rear view of the liquid cooled motor of FIG. 1.

The dashed lines shown in FIGS. 6 and 7 do not form part of the claimed design.
